FIG. 3

FIG. 4

FIG. 5

FIG. 6

FIG. 7

FIG. 8

FIG. 9

FIG. 1 is a perspective view of a swimming pool having a round shape embodying my new design;

FIG. 2 is a plan view of the pool shown in FIG. 1;

FIG. 3 is a side elevational view of the pool shown in FIG. 1;

FIG. 4 is a perspective view of the swimming pool having an oval shape embodying my new design;

FIG. 5 is a plan view of the pool shown in FIG. 4;

FIG. 6 is a side elevational view of the pool shown in FIG. 4;

FIG. 7 is a perspective view of the swimming pool having an oval shape with molded-in seats embodying my new design;

FIG. 8 is a plan view of the pool shown in FIG. 7; and

FIG. 9 is a side elevational view of the pool shown in FIG. 7.

The dominant feature of my design resides in an integral slide projecting above the circumferential flange and having hand rail portions extending upwardly therefrom in the general plane of the sliding surface.

I claim:

The ornamental design for a swimming pool, substantially as shown and described.
